CHINA BREAKFRONT

Joseph E. Atkinson, 3807 Leland St.,
Chevy Chase, Md. 20015

Filed Feb. 4, 1972, Ser. No. 223,824

Term of patent 14 years

Int. Cl. D6—04

U.S. Cl. D6—154

FIG.1

FIG.2

FIG. 1 is a view in front elevation of the china breakfront showing my design.

FIG. 2 is a view in side elevation of the china breakfront of FIG. 1.

The back of the china breakfront is conventionally flat; the side not shown is identical to the side shown in FIG. 2, and the top is plain.

I claim:

The ornamental design for a china breakfront, or the like substantially as shown and described.
